TOY RAPID-FIRE GUN

Walter Trubenbach, Bloomfield, and Frank Warholick, Irvington, N. J.

Application December 21, 1931
Serial No. 582,304

2 Claims. (Cl. 124—13)

This invention relates to an improved construction of rapid-fire gun in the form of a toy for children; and the invention has for its principal object to provide a novel and simple toy gun capable of holding a comparatively large supply of projectiles, and operative to successively discharge the stored projectiles with great rapidity until the supply thereof is exhausted.

The invention has for a further object to provide a novel magazine for holding the supply of projectiles, which also serves as a shoulder brace or stock for steadily supporting the gun in the hands of the user, while the latter is aiming and discharging the gun.

15. The invention also has for an object to provide a novel form and arrangement of firing pin, which, in a position of rest, serves as a detent for retaining projectiles against undesired escape from the magazine; and the invention has for another object to provide means to retain projectiles against outward movement through the gun barrel, until operatively subjected to discharging impact of the firing pin.

25. Other objects of this invention, not at this time more particularly enumerated, will be understood from the following detailed description thereof.

30. An illustrative embodiment of the invention is shown in the accompanying drawing, in which:

Fig. 1 is a side face view of the toy rapid-fire gun according to this invention; and Fig. 2 is a central longitudinal vertical section through the same, drawn on an enlarged scale, with the firing-pin shown in projectile detaining position; Fig. 3 is a fragmentary view, similar to that of Fig. 2, but showing the firing bolt and firing-pin retracted to release a projectile from the magazine and into alignment with the gun barrel ready for discharge through the latter under the impact of the released firing bolt and its firing-pin; Fig. 4 is a detail transverse section, taken on line 4—4 in Fig. 2; Fig. 5 is a detail transverse section taken on line 5—5 in Fig. 3; and Fig. 6 is a detail transverse section, taken on line 6—6 in Fig. 2.

45. Similar characters of reference are employed in all of the above described views, to indicate corresponding parts.

50. Referring to said drawing, the toy gun according to this invention comprises a longitudinally divided body to form meeting halves or shells 10 and 11 which are suitably secured together in operative assembled relation by transverse bolts 12, or by any other suitable fastening means. The body portions 10 and 11 may be made of cast

or sheet metal, wood or any other desired suitable material. The body portions, when joined together, are designed to provide a chambered breech-portion 14, from the forward end of which projects the barrel 15, and at the rearward end 60 of which is a grip portion 16. Extending upwardly and rearwardly from the breech-portion 14 is a magazine section 17, which is shaped somewhat in the form of a gun-stock, the butt of which may be rested against the body or shoulder of the operator of the gun so as to steady the same when directing the pointing or aiming thereof. The interior of the magazine is divided from the interior of the breech-portion 14 by a partition 18, which is so shaped as to define a 65 restricted magazine discharge passage 19 of a cross-sectional area just sufficient to pass marble or ball-like projectiles 20 singly therethrough from the interior of the magazine. The discharge or outlet end of said passage 19 communicates with the bore 2 of the barrel 15, at a point adjacent to the inner or rearward end of the latter. The outer rearward end of the magazine is closed by an inverted conical or funnel-like 70 end wall 22, having a central loading opening 23 through which the projectiles 20 may be passed 75 in filling up the magazine interior therewith.

80. Fixed within the interior of the breech-portion 14 is a guide member 24 having at its ends laterally extending guide tongues 25 and 26; the forward guide-tongue 25 being disposed adjacent to and rearwardly of the juncture of the magazine discharge passage 19 and barrel bore 21, and aligned with the latter. Supported by said guide member 24 for longitudinal movements is a firing bolt 27, the body of which is preferably of rectangular cross-section. The firing bolt is provided at its forward end with a firing pin 28 of reduced cross-section, whereby a stop shoulder 29 is provided at the juncture of these parts. The forward 85 guide-tongue 25 is provided with a perforation 90 sized to permit the extension of the firing pin 28 therethrough to normally project into the rearward end of the barrel bore 21 and so as to underlie the discharge end of the magazine discharge 95 passage 19, such normal position of the firing pin 28 being determined by the abutment of the stop-shoulder 29 against the rear face of said guide-tongue 25. The rearward guide-tongue 26 100 is provided with an opening shaped to correspond to the cross-sectional shape of the firing bolt 27, whereby the rearward end 30 of the latter projects slidably through the former. A power spring 31 105 is suitably secured by one end to a wall of the breech-portion 14 in such disposition that its free 110

end bears thrustingly against the rear end of the firing bolt 27 to urge the latter to the described normal position. Secured to and projecting upwardly from the firing bolt 27 is a retracting stud 32. Journaled in and extending transversely between the side walls of the breech-portion 14, above the firing bolt 27 is a rotatable shaft 33, which is provided on an exteriorly projecting end with a crank-handle 34, by which the user of the gun may rotate the same. Fixed on the interior portion of said shaft 33, so as to be revolved by rotation of the latter, is a cam or retractor arm 35, so disposed as to operatively engage, retract and then release the retracting stud 32 of the firing bolt 27 at each revolution imparted to the former, thereby retracting the firing bolt and its firing pin preparatory to release of the same for forward firing movement.

Preparatory to the operation of the gun, the user will store a supply of projectiles 20 within the magazine interior, by passing said projectiles through the loading opening 23 into the magazine interior until the same is filled up. The position, form and relation of the magazine to the gun barrel and firing mechanism is such that a magazine of generous projectile storage capacity is provided, adapted to hold at one loading a very considerable number of ball-like projectiles. The stored projectiles, owing to the downward inclination and direction of the magazine and its discharge passage when the gun is held in firing position, assures the constant gravitation of the stored projectiles into the discharge passage in a train and subject to successive release therefrom one at a time for deposit in the rearward end of the barrel bore 21 at each reciprocation of the firing bolt and firing pin. Normally, as has been stated, the firing pin 28 underlies the lowermost projectile 20 which is lodged at the end of the discharge passage 19 ready for deposit within the barrel bore; the firing pin 28 thus serving, when in normal position, as a detent for holding back uncontrolled discharge of the projectiles from the storage magazine.

When the gun is loaded, the user grasps the grip portion 16 in one hand, and lodges the butt end of the magazine portion against the shoulder or body, thus steadily holding the gun in firm, unwavering position with the barrel 15 directed and aimed as desired. With the gun thus held and aimed, the user grasps the crank-handle 34 with the free hand and turns the same to thereby rotate the shaft 33 to cause revolution of the cam or retractor arm 35 in the direction of the arrows shown in Figs. 2 and 3 of the drawing. As the cam or retractor arm 35 revolves, its free end moves against the retracting stud 32 to thrust rearwardly upon the same, thus sliding back or retracting the firing bolt 27 and firing pin 28, against the tension of the spring 31, until the firing pin 28 is withdrawn from beneath the lowermost projectile 20 ready for release from the discharge passage 19 of the magazine. This withdrawal of the firing pin 28 allows said projectile 20 to drop down into the rearward end of the barrel bore 21, so as to lie in alignment therewith and in front of the retracted firing pin. In order to prevent premature outward movement of the thus positioned projectile through the barrel bore and away from the sphere of influence of the firing pin, a yieldable check means is provided to engage the projectile and obstruct such premature outward movement thereof. This check means is preferably in the form of a flat detent spring 36, suitably secured to the underside of the barrel 15, and provided with an upturned free end portion

37 which extends through an opening 38 in the underside of the barrel 15 to engage the forward side of the deposited projectile. As the revolution of the cam or retractor arm 35 continues it eventually passes out of engagement with the retracting stud 32, thereby releasing the retracted firing bolt 27. The tension of the power spring 31, upon release of the retracted firing bolt 27, induces a powerful forward movement of the same in its guide means, thus powerfully projecting the firing pin 28 with sharp impacting effect against the deposited projectile 20, whereby the latter is propelled outwardly through the barrel bore 21. Continued rotation of the shaft 33 and cam or retractor arm 35 successively and rapidly repeats the above described projective firing operations, until the supply of projectiles carried in the magazine is exhausted.

From the above it will be obvious that the present invention provides a simple and yet efficient toy rapid fire gun capable of affording pleasurable amusement to children, while being of such construction and arrangement that no risk of injury to the child when using the same is involved.

As many changes could be made in the construction and many apparently widely different embodiments of this invention could be made without departing from the scope thereof, it is intended that all matter contained in the above description or shown in the accompanying drawing shall be interpreted as illustrative and not in a limiting sense.

What is claimed is:—

1. A toy rapid-fire gun, comprising a hollow body having a barrel projecting forwardly therefrom, a projectile storage magazine having a discharge passage communicating with the rearward end of the bore of said barrel, said magazine being disposed relative to said barrel so as to feed projectiles by gravity thereto, a longitudinally slidable firing-bolt aligned with and rearwardly disposed relative to said barrel, said firing-bolt having a firing pin to normally enter said barrel and underlie the magazine discharge passage to detain projectiles against release from the magazine until said firing-bolt is retracted, a guide member within the hollow body having perforate tongues to slidably support and guide said firing bolt, a power spring bearing on the rearward end of said firing-bolt for imparting firing impulse thereto, a retracting stud projecting angularly upward from said firing-bolt intermediate its ends, a shaft transversely journaled in said body above said firing-bolt and having external means for manually rotating the same, and a cam arm revolvable by said shaft and cooperative with said retracting stud for retracting and releasing said firing-bolt.

2. A toy rapid-fire gun, comprising a breech-portion having a barrel projecting from its forward end and a grip-portion connected with its rearward end, a projectile magazine projecting upwardly and rearwardly from said breech-portion, said magazine having a discharge passage communicating with the rear end of said barrel so as to feed projectiles one at a time by gravity into the latter and subject to the action of said firing mechanism, the free end wall of said magazine being of inverted conical shape and having an opening at its inner apex end through which projectiles may be loaded into said magazine, a firing mechanism comprising a longitudinally slidable firing-bolt, means within said breech-portion to guide said firing-bolt, said firing-bolt

having a firing-pin to normally enter said barrel and underlie the magazine discharge passage to detain projectiles against release from the magazine until said firing-bolt is retracted, a power 5 spring for imparting firing impulse to said firing-bolt and pin, a retracting stud projecting angularly from said firing-bolt, a shaft journaled in

said breech-portion and having an external crank-handle for rotating the same, and a cam arm revolvable by said shaft and cooperative with said retracting stud for retracting and releasing said firing-bolt and pin. 80
